(57) **CLAIM**

The ornamental design for a set of interproximal brushes with case, as shown and described.

DESCRIPTION

FIG. 1 is a perspective view of the case portion of our new design, the brushes being omitted for ease of illustration only;

FIG. 2 is a front elevation view of the set of interproximal brushes with case, with the three brushes fitted therein;

FIG. 3 is a right side elevation view of FIG. 2;

FIG. 4 is a rear elevation view of FIG. 2;

FIG. 5 is a left side elevation view of FIG. 2;

FIG. 6 is a top plan view of FIG. 2;

FIG. 7 is a bottom plan view of FIG. 2;

FIG. 8 is a reduced, inverted front elevation view of FIG. 2 with one of the brushes inverted for clarity of illustration;

FIG. 9 is a right side elevation view of FIG. 8;

FIG. 10 is a rear elevation view of FIG. 8;

FIG. 11 is a left side elevation view of FIG. 8;

FIG. 12 is a top plan view of FIG. 8; and,

FIG. 13 is a bottom plan view of FIG. 8.
